DESIGN FOR A CAP

Isidore Borten, New Haven, Conn.

Application February 26, 1943, Serial No. 109,633

Term of patent 3½ years

To all whom it may concern:

Be it known that I, Isidore Borten, a citizen of the United States of America, residing in New Haven, county of New Haven, and State of Connecticut, have invented a new, original, and ornamental Design for a Cap, of which the following is a specification, reference being had to the accompanying drawing, forming part thereof, wherein:

I claim:

The ornamental design for a cap, substantially as shown.

ISIDORE BORTEN.
